4 Claims. (Cl. 110—18)

Our present invention relates to an incinerator for paper, cardboard and similar combustible household waste.

Is is the general object of our invention to provide a preferably portable incinerator for such materials adapted to burn even heavy and/or coated paper products, such as oil or wax papers, in a substantially complete and soot-free manner so that only smokeless flue gases are developed and the need for connecting the exhaust of the device to a chimney is eliminated. A more particular object of the invention is to realize these advantages in an incinerator free from grates, stokers and other movable parts.

We have found, in accordance with our instant invention, that these objects may be realized in a simple and efficient manner by the provision of an incinerator having a perforated shell which terminates at the top in a flue and forms at the bottom a combustion chamber in combination with that flue, the shell containing in the interior of the combustion chamber one or more inlets for supplemental combustion air. Such an inlet advantageously takes the form of an upstanding tubular boss, preferably of generally frustoconical configuration like the surrounding shell, the tip of the boss extending approximately midway into a combustion zone defined by a lower shell section above a bottom section designed to receive the combustible material. The interior of the tubular boss communicates with the exterior of the shell, e.g. through suitable conduits or through a bottom aperture, so that air simultaneously enters the combustion zone from within and without whereas a flame started at the top of the rubbish pile within the chamber spreads progressively downwardly with substantially complete conversion of the waste products into smokeless gases. As these gases escape upwardly through the flue, more air is drawn in through the peripheral shell perforations and the supplemental inlet means, this air being advantageously preheated by the preferably metallic walls of the inlet-forming boss. Any fly ash or cinders entrained by the escaping flue gases can easily be intercepted and returned to the combustion chamber by a screen spanning the entrance to the flue within the shell.

The invention will be described in greater detail with reference to the accompanying drawing in which:

FIG. 1 is an elevational view, partly in section, of an incinerator embodying the present improvement; and

FIG. 2 is a sectional elevational view of a modified bottom section for such incinerator.

The incinerator shown in FIG. 1 comprises a shell composed of a cylindrical bottom section 1, a lower frustoconical section 4 and an upper frustoconical section 5, these sections being stacked upon one another so as to define a progressively constricted path for ascending combustion gases whereby the latter are thoroughly intermingled with the admixed air. The air enters the interior of the shell through several annular rows of perforations disposed in different horizontal planes, such as the apertures 1c of section 1 and the apertures 4b, 4c of section 4. The aforementioned apertures, as also similar apertures in section 5, are partly covered up from the outside by overhanging baffle portions 1d, 4e, 4f, other baffles 5a, 5b, 5e on shell section 5 overlying similar

2

perforations in the upper part of the incinerator. Section 5 terminates at the top in a flue 5c whose lower end is spanned by a screen 6. Section 4 is provided with a series of latch fingers 4a, releasably engaging respective lugs 5e on section 1, and with a top flange 4g similarly engaged by catches 5d on section 5. Handles 4d on section 4 and 5f on section 5 enable these sections to be lifted off for filling and cleaning purposes.

An inlet for supplemental air in accordance with this invention is provided in the shape of a frustoconical boss 3 rising off the bottom of section 1. This boss, whose walls are formed with numerous openings 3a, rises to substantially the median level of shell section 4 and is open at the bottom for communication with the atmosphere; as shown, it also has a narrow opening at the top. The bottom of shell section 1, which constitutes a receptacle for the rubbish to be burned, is provided to this end with a central hole 1b receiving the base of boss 3. This bottom, raised above its supporting surface by legs 2, is also shown formed with numerous small perforations 1a through which further air can enter the interior of the shell. Section 4, which as shown is of somewhat greater height than boss 3, is imperforate above the top of the boss, the rows of aperture 4b, 4c being confined to its bottom half.

In operation, the incinerator shown in FIG. 1 is filled upon removal of the upper or covering section 5 with the waste products to be burned, this material being then ignited before section 5 is put back in place. The initial combustion stage results in the escape of gases through the flue 5e and draws atmospheric air through the external shell apertures 1c, 4b, 4c etc. and also through the openings 3a of the internal inlet 3. It will be apparent that the baffles 1d, 4e, 4f etc. prevent the flame from shooting out through the peripheral shell apertures. Screen 6 will intercept any glowing particles rising toward the flue 5c and return them to the interior of the shell for further combustion. The updraft created within the shell will generally be strong enough to prevent any solids from dropping through the bottom apertures 1a of receptacle 1; if desired, however, a pan designed to catch any falling ashes may be placed between the legs 2.

In FIG. 2 we have shown a modified waste receptacle 1' for our improved incinerator which has an imperforate bottom supporting the boss 3', the interior of this boss communicating with the exterior of the shell portion 1' through a plurality of horizontal conduits 7. The air entering through these conduits passes, as in the preceding embodiment, into the combustion zone of the shell through the apertures 3a' of the boss. The legs 2 of FIG. 1 have been omitted in this arrangement.

It will thus be seen that we have created an improved incinerator, especially for household use, in which thorough combustion of cellulosic and other combustible waste products is achieved without the use of any movable parts. Departures from the precise arrangement shown and described, e.g. as to the number of inlets 3 or 3', the shape and number of the several shell sections and the type of fastening means employed to hold them together, are of course possible without departing from the spirit and scope of the invention as defined in the appended claims.

We claim:

1. An incinerator for combustible waste materials, comprising a generally conical shell surrounding a combustion chamber, said shell converging upwardly and terminating at the top in a centrally positioned flue communicating with said chamber, said shell being further provided with peripheral apertures for admitting air into said chamber, and inlet means for additional air positioned within said shell near the bottom of said combustion chamber, said inlet means comprising at least one centrally positioned upstanding perforated tubular boss with-

in said combustion chamber, the interior of said boss communicating with the exterior of said shell, said boss converging substantially conically toward the top, said shell being composed of a bottom section and a plurality of frustoconical sections stacked upon one another, said sections being provided with fastening means for releasably interconnecting them, said boss rising from said bottom section to substantially the median level of the next higher section, the latter being of a height exceeding that of said boss and having said peripheral apertures disposed only in its bottom half below the top of said boss.

2. An incinerator according to claim 1 wherein said shell is provided with a generally horizontal screen spanning its interior near the bottom of said flue.

3. An incinerator according to claim 1 wherein said shell is provided with baffles externally overhanging said apertures from above.

4. An incinerator for the self-combustion of combustible waste materials, comprising an annular support section having air-inlet means distributed peripherally about said support section, and an axially extending centrally disposed upstanding perforated tubular boss having a generally conical configuration, said boss being provided with an inlet for admitting air through the perforation thereof to the interior of said support section; an upright bi-partite combustion-chamber shell mounted on said support section, said shell comprising a frustoconical lower section for containing waste material mounted on said annular support section with said boss projecting into said lower section over at least half the axial length of said lower section, said lower section being provided with a multiplicity of peripheral air-inlet apertures disposed

5
10

in a relatively narrow band at a lower portion of said lower section and with a relatively wide imperforate band at an upper portion, and a frustoconical upper section removably stacked on the tapering upper extremity of said lower section, said upper section being provided with a multiplicity of peripheral apertures located in a plane substantially above said extremity for admitting air into said upper section; means enabling removal of said upper section from said lower section, thereby permitting the ignition from above of said waste materials contained in said lower section; and a flue of generally cylindrical configuration surmounting the tapering upper extremity of said upper section.
